UNITED STATES PATENT OFFICE.

FERDINAND L. SCHMIDT, OF NEW YORK, N. Y., ASSIGNOR TO UNITED STATES ENVELOPE COMPANY, OF SPRINGFIELD, MASSACHUSETTS, A CORPORATION OF MAINE.

ENVELOP-MACHINE.

1,152,555.

Specification of Letters Patent.

Patented Sept. 7, 1915.

Application filed November 5, 1909. Serial No. 526,358.

To all whom it may concern:

Be it known that I, FERDINAND L. SCHMIDT, a citizen of the United States, residing at New York, in the county of New York and State of New York, have invented a new and useful Improvement in Envelop-Machines, of which the following is a specification, accompanied by drawings, forming a part of the same, in which—

10 Figure 1 is a plan view of an envelop machine embodying my invention. Fig. 2 is a side elevation, with parts shown in sectional view on the line 2—2, of Fig. 1. Fig. 3 is a front elevation of a portion of the patch applying mechanism. Fig. 4 is a side view of the same shown in sectional view. Fig. 5 is a side view of the patch applying mechanism, shown in sectional view, showing the operative parts in position at the 20 period of applying a patch to an envelop blank, and Fig. 6 is a plan view of an envelop blank having an opening in the body portion covered by a transparent patch.

Similar reference characters refer to similar parts in the different figures.

My present invention relates to an envelop machine for making what are known as outlook envelopes, or envelopes in which the body of the envelop is provided with an opening adapted to register with an address written or printed upon an inclosure, said opening being covered with a transparent patch which renders an inclosed address visible.

35 The object of my present invention is to complete the manufacture of an outlook envelop upon a single machine, capable of gumming the flaps of the envelop, punching a hole or window in the body portion of the 40 blank, gumming around the margin of the window, applying a patch to the gummed margin for closing the opening and folding the flaps of the envelop, and this object I accomplish by combining with the flap gumming and flap folding mechanisms of an envelop machine means for punching and gumming the window opening and applying a patch thereto, as hereinafter described and pointed out in the annexed claims.

50 The construction and operation of the flap gumming and flap folding mechanisms will be well understood by those conversant with envelop machines, and in the accompanying drawings I have, therefore, shown so much

of an envelop machine as will be necessary to illustrate my present invention.

The flap gumming mechanism comprises a table or support 1 for a stack or pile of envelop blanks 2, the topmost blank of which is raised at stated periods by means of vertically reciprocating flap gumming dies 3, 3, which are gummed by reciprocating gumming rolls 4, 4 taking gum at one end of their reciprocating movement from a roll 5, which revolves partially immersed in gum contained in the gum pan 6. As the topmost blank is raised from the stack 2, a reciprocating hooked conveyer 7 is moved back over the stack of blanks in position to catch and support the raised and gummed envelop blank as it is stripped from the gumming dies by a stripping plate 8. The conveyer 7 then moves forward causing the blank, which is engaged by the hooks 9, to be carried over a die plate 10 and into the position indicated by the blank 11, Fig. 1, in proper position to be punched by a vertically reciprocating punch 12 which, at the proper period, is made to pass downward by suitable actuating mechanism into an opening 13 in the die plate 10, thereby forming an opening in the body of the envelop, such as that shown at 14, Fig. 6.

In the present instance the reciprocating punch 12 is connected by a link 15 with one end of a lever 16 which is pivoted upon the framework of the machine, and has its opposite end connected with a cam 16^a. Surrounding the reciprocating punch 12 is a sleeve 17, connected by links 18 with a lever 19 pivoted on the framework of the machine and operatively connected with an actuating cam, not shown. The sleeve 17 is preferably provided at its lower end with a yielding face 20 of rubber, or similar material, to which gum is applied by a reciprocating gumming roll 21 in the usual manner of applying adhesive material to the gumming dies of envelop machines.

The mechanism for holding the blank under the punch 12, punching the opening in the blank and gumming the margin around the opening forms no part of my present invention, it having been fully described in Letters Patent of the United States issued to me July 11, 1911, No. 997,330, and the same is represented in the accompanying drawings simply for the purpose of show-

ing its relative position to the flap gumming and flap folding mechanisms of the envelop machine.

When the envelop blank has been punched by the reciprocating punch 12 and die plate 10, hooks 22 on the conveyer carry the blank forward over a table 23 and beneath a vertically reciprocating plunger 24 which, upon its downward movement, forces the body of the blank through an opening 25 in the table 23 upon a folding bed 26 where the flaps are folded by hinged flap folders 27, 28 and 28^a in the method commonly practised in envelop machines of this class. When the envelop rests upon the table 23 in the position shown at 30, Fig. 1, and before the plunger begins its downward movement, a patch of transparent paper 29, Fig. 6, is applied to the envelop blank to cover the opening 14.

20. The patch 29 is of sufficient size to cover the gummed surface formed by the contact of the yielding gummed face 20 of the sleeve 17 with the envelop blank.

The transparent patch 29 is cut from the end of a continuous strip 31 taken from a coil 32 supported in the frame-work of the machine in an elevated position in front of the folding mechanism. The mechanism for withdrawing the continuous strip from the coil 32, cutting the individual patch therefrom and applying the same to an envelop blank is shown in sectional view in Fig. 2, but is represented on a larger scale in Figs. 3, 4 and 5, the sectional views represented in Figs. 4 and 5 showing the cutting and patch applying mechanisms in different positions, that shown in Fig. 4 showing the cutting mechanism in the position of severing the patch from the continuous strip and Fig. 5 representing the severed patch as being applied to the envelop blank.

The continuous strip is withdrawn from the coil 32 by means of feed rolls 33 and 34, the former of which is driven by a sprocket 45 wheel 35 and chain 36 from a driving shaft 37, imparting a slow feeding movement to the continuous strip 31 by which it is projected through a tubular guideway 38 to the cutting mechanism, which comprises a stationary cutting blade 39 and a movable cutting blade 40. The movable cutting blade is carried in a swinging arm 41 pivoted on a rocking shaft 42, and provided with ways 43 in which the movable blade is capable of sliding. The swinging arm 41 is provided with a central opening 44, through which pass downwardly projecting arms 45 carried by the rocking shaft 42. The arms 45 pass through a hole in the movable cutting blade 40, and the lower ends of the arms 45 are connected by spiral springs 46 with studs 47 projecting from the lower end of the swinging arm 41. The swinging arm 41 is provided with a pressure plate 48, between which and the stationary cutting blade 39

the free end of the continuous strip 31 is clamped by the swinging movement of the arm 41. An intermittent rocking motion is given to the shaft 42 and arms 45 by means of a radial arm 49, carried on one end of the rocking shaft 42 and connected by a link 50 with a suitable actuating cam carried upon the shaft 37.

When the arm 41 is swung away from the stationary blade 39, as shown in Fig. 5, the end of the continuous strip 31 is moved forward over the corner of the stationary blade 39 a sufficient distance to form the width of the patch 29. A swinging movement is then given to the arm 41 to carry it from the position shown in Fig. 5 to the position shown in Fig. 4, the arm 41 being drawn forward by means of its spring connections 46 with the ends of the arms 45. During this swinging movement of the arm 41, the movable cutting blade 40 is held retracted within the ways 43 until the pressure plate 48 clamps the end of the continuous strip against the stationary cutting blade 39, thereby stopping the forward movement of the arm 41. The continued movement of the arms 45 will then slide the movable cutting blade in its ways 43 over the edge of the stationary cutting blade 39, thereby severing the individual patch from the continuous strip. The severed patch is then held firmly between the pressure plate 48 and the stationary cutting blade 39, with the lower edge of the patch covering the open ends 51 of a pair of suction tubes 52 carried upon a hollow rocking shaft 53. The suction tubes 52 communicate with the hollow shaft 53, and the latter is connected by a flexible tube 54 with a pump or other suitable mechanism, not shown, for exhausting the air from the suction tubes 52 during their period of contact with the severed patch.

As soon as the patch has been severed from the end of the continuous strip, the motion of the rocking shaft 42 is reversed, swinging the arms 45 away from the stationary cutting blade 39 into the position shown in Fig. 5, and again providing a free space between the stationary cutting blade 39 and the pressure plate 48 for the feeding movement of the continuous strip, but leaving the severed patch securely held against the open ends of the suction tubes 52. The rocking shaft 53, which carries the suction tubes 52, is then rocked by means of a radial arm 55 and link 56 which connects the radial arm 55 with a suitable actuating cam, not shown, on the shaft 37. The rocking movement of the shaft 53 carries the suction tubes 52 from a vertical position to a horizontal position, as shown by the broken lines 57, Fig. 4.

The hollow rocking shaft 53 is journaled in a sliding frame 58 movable in horizontal ways 59. The frame 58 is provided with

friction rolls 60 which are held against cams 61 carried upon a rocking shaft 62, having a radial arm 63 connected by a link 64 with an actuating cam carried on the shaft 37, not shown. When the suction tubes have been brought into the horizontal position indicated by the broken lines 57, Fig. 4, a rocking movement is imparted to the cam 61 which forces the sliding frame 58 rearward, thereby moving the suction tubes 52 from the position shown by the broken lines 57 to the position shown by the broken lines 65 and beneath the reciprocating plunger 24. A second rocking movement is then given to the hollow rocking shaft 53, by which the open ends of the suction tubes 52 are depressed to carry the severed patch held thereon into contact with the gummed surface of the envelop blank. As soon as the severed patch is brought into contact with the gummed surface of the envelop blank, the suction is withdrawn, thereby releasing the patch from the suction tubes which have been restored to their normal vertical position, as shown in Fig. 4, by a reversal of the movements already described.

The width of the patch may be determined by varying the speed of the sprocket wheel 35. The length of the patch is determined by the width of the continuous strip 31 and the position in which the severed patch is delivered to the envelop blank may be varied by changing the form of the cams 61. The shape of the cams 61 determines the horizontal movement given to the frame 58 beneath the plunger 24, thereby enabling the position of the opening 14 to be varied in the body of the envelop as desired and a patch to be applied in perfect registration with the opening.

I claim,

1. In an envelop machine, the combination of the following instrumentalities: a die plate, means for gumming the flaps only of an envelop blank, means for feeding the gummed blank upon said die plate, means for forming an outlook opening in the body of said gummed blank upon said die plate, means for gumming said blank upon said die plate around said outlook opening, a creasing plate, means for feeding said gummed blank upon said creasing plate, means for applying a patch of paper directly to said gummed outlook opening in said blank upon said creasing plate, a plunger arranged to force said blank after it has received said patch through an opening in said creasing plate, and means for folding the flaps of said blank.

2. In an envelop machine, the combination with means for gumming the flaps only of an envelop blank and means for folding said flaps, of means for feeding said blank from said gumming mechanism to said folding mechanism with an intervening period

of dwell, and means for forming an outlook opening in the body of said blank and gumming around said opening during said period of dwell.

3. In an envelop machine, the combination with means for gumming the flaps only of an envelop blank and means for folding said flaps, of means for feeding said blank from said gumming mechanism to said folding mechanism with an intervening period of dwell, means for forming an outlook opening in the body of said blank and gumming around said opening during said period of dwell, and means for applying a patch of paper directly to said outlook opening after said blank has reached said folding mechanism, but before the operation of said folding mechanism begins.

4. In an envelop machine, the combination of the following instrumentalities acting in the order named: means for gumming the flaps of an envelop blank, means for forming an outlook opening in the body of said gummed blank, means for gumming around said opening, means for applying a patch of paper to said gummed opening, means for folding the flaps of said blank, and means for progressively feeding said blank.

5. In an envelop machine, the combination with a creasing table and a reciprocating plunger for pushing an envelop blank through said creasing table, of means for carrying an individual patch by a horizontal movement between said creasing table and said plunger, and means for holding said patch in fixed relation to said carrying means during said horizontal movement.

6. In an envelop machine, a creasing table, a reciprocating plunger for forcing an envelop blank through said creasing table, carrying means for transferring an individual patch of paper to a blank supported on said creasing table, means for holding the patch from movement relatively to said carrying means, and means for imparting a predetermined horizontal movement to said carrying means to carry the patch between the plunger and the creasing table.

7. In an envelop machine, a creasing table, a reciprocating plunger, means for carrying an envelop blank having an opening and a gummed margin around said opening between said creasing table and said plunger, means for carrying an individual patch of paper between the plunger and creasing table, means for maintaining the patch in fixed relation to said carrying means during its movement, and means for imparting a predetermined movement to said carrying means to bring the patch into registration with the opening in the envelop blank.

8. In an envelop machine, the combination with a creasing table and a reciprocating plunger for pushing an envelop blank through an opening in said table, of a suc-

- tion tube pivotally mounted to engage in an upright position a patch of paper and movable into a horizontal position to carry said patch above said creasing table, and means for rocking said tube.
9. In an envelop machine, the combination with a creasing table and a reciprocating plunger for pushing an envelop blank through an opening in said table, of a suction tube pivotally mounted to engage in an upright position a patch of paper and movable into a horizontal position to carry said patch above said creasing table, means for rocking said tube, and means for horizontally moving said suction tube to carry said patch held by said tube beneath said plunger.
10. In an envelop machine, the combination with a creasing table and a reciprocating plunger for pushing an envelop blank through an opening in said table, of a suction tube pivotally mounted to engage in an upright position a patch of paper and movable into a horizontal position to carry said patch above said creasing table, means for rocking said tube, and means for horizontally moving said suction tube to carry said patch held by said tube beneath said plunger, said horizontally moving means adjustable to vary the position of the application of said patch.
11. In an envelop machine, the combination with a creasing table and a reciprocating plunger for pushing an envelop blank through an opening in said table, of a suction tube pivotally mounted to engage in an upright position a patch of paper and movable into a horizontal position to carry said patch above said creasing table, means for rocking said tube, and means for horizontally moving said suction tube to carry said patch held by said tube beneath said plunger and above said creasing table, said suction tube arranged to be rocked further to depress said patch.
12. In an envelop machine, the combination with a creasing table and a reciprocating plunger for pushing an envelop blank having a gummed opening through an opening in said table, of a shaft with a suction tube extending radially from said shaft, said tube arranged to engage in an upright position a patch of paper and movable into a horizontal position to carry said patch immediately above said table, means for rocking said shaft, means for moving said shaft horizontally to carry said patch into registration with said gummed opening in the envelop blank, and with said shaft also arranged to be rocked further to depress the end of said radial tube to carry said patch into contact with said gummed opening.
13. In an envelop machine, the combination with a creasing table and a reciprocating plunger for forcing a blank through an opening in said table, of means for inserting a patch of paper between said creasing table and said plunger, comprising a suction tube, means for feeding a continuous piece of paper over the end of said suction tube, means for severing the continuous strip, means for rocking said suction tube, means for moving said suction tube at right angles to the movement of said plunger, means for imparting a second rocking movement to the suction tube to depress the patch of paper, and means for restoring the suction tube to a position to receive the succeeding patch.
14. In an envelop machine, the combination with a creasing table and a reciprocating plunger, of mechanism for applying an individual patch to an envelop blank on said creasing table, comprising a rocking shaft, a suction tube carried by said shaft, means for applying a patch of paper to said suction tube, means for rocking said shaft, and means for moving said shaft sidewise in a plane at right angles to the movement of said plunger to carry the end of said suction tube between the plunger and the creasing table.

Dated this first day of November, 1909.
FERDINAND L. SCHMIDT.
